UNITED STATES PATENT OFFICE

2,516,170

HYDRAULIC PRESS INTENSIFIER
ATTACHMENTCecil E. Adams, Columbus, Ohio, assignor to The
Denison Engineering Company, Columbus,
Ohio, a corporation of Ohio

Application February 24, 1947, Serial No. 730,593

7 Claims. (Cl. 66—52)

1

This invention relates to hydraulic apparatus and is, in its more specific aspects, directed to hydraulic pressing mechanism. Still more specifically, the invention is directed to an attachment for presses by which the force exerted by the pressing ram may be intensified or multiplied.

One of the objects of this invention is to provide an attachment for a press which may be used with presses of low pressing force to perform pressing operations requiring high pressing forces.

Another object is to provide an attachment of the type mentioned in the preceding paragraph which will be operated entirely by hydraulic pressure.

A further object of the invention is to provide a hydraulic attachment for a press which will be operated entirely by the motion of the ram of the low capacity press to which it is applied to develop pressing forces of high tonnage.

A still further object of the invention is to provide mechanism for attachment to a press to be operated by the ram thereof, which mechanism includes a second ram and means for transmitting motion from the ram of the first press to the second ram to cause the same to move relatively rapidly until a certain resistance is encountered and then slowly and with increased force, the transition from low to high force taking place automatically and without attention or action by the operator.

Another object is to provide a hydraulic mechanism for use with a hydraulically actuated ram for multiplying the force of the ram without changing or otherwise altering the hydraulic circuit containing the ram.

Another object is to provide a press attachment for intensifying the force applied to the press ram, the attachment having a fluid transmitter and translator, the former being operated by the pressing ram and the latter having a second ram, the attachment including mechanism for multiplying the effectiveness of the transmitter.

A further object is to provide an attachment for a hydraulic press having a ram, the attachment also having a ram and a hydraulic motion-transmitting mechanism whereby movement of the ram of the press will cause similar movement of the ram of the attachment, the motion-transmitting mechanism having a transmitter and a translator with pistons of predetermined relative areas and means for changing the relation of the piston areas during a cycle of operation of the press and attachment.

Another object is to provide an attachment for a hydraulic press, the attachment having a ram

2

disposed for sliding movement in a cylinder and a pump-like device having a piston movable in a cylinder, the piston being directly connected with the ram of the press, movement of the ram serving to cause the piston to pump fluid into the cylinder of the attachment to cause movement of the ram thereof, the attachment having means responsive to fluid pressure generated by resistance to movement of the ram thereof to establish communication between opposite ends of the pump cylinder whereby the effective area of the pump piston will be reduced to the area of the piston rod connecting the piston to the press ram. Through the reduction of the piston area in this manner a differential effect will be produced which will multiply the force developed by the press ram in the ratio which the area of the piston rod bears to the area of the ram of the attachment.

20 Further objects and advantages of the present invention will be apparent from the following description, reference being had to the accompanying drawings wherein a preferred form of embodiment of the invention is clearly shown.

25 In the drawings:

Fig. 1 is a diagrammatic view of a hydraulic system employed in a press and attachment formed in accordance with the present invention.

Fig. 2 is a side elevational view of a press and attachment embodying the present invention.

30 Fig. 3 is a detail vertical sectional view taken through one portion of the attachment, this portion constituting the transmitter of the motion-transmitting mechanism.

35 Fig. 4 is a detail vertical sectional view taken through another portion of the attachment, this portion including the translator of the motion-transmitting mechanism and apparatus operated thereby.

40 Fig. 5 is a detail longitudinal sectional view taken through an automatic valve forming a part of the attachment, on the plane indicated by the line V—V of Fig. 3.

45 Figs. 6 and 7 are detail vertical sectional views taken through the automatic valve shown in Fig. 5, the sections being taken on the planes indicated by the lines VI—VI and VII—VII, respectively, of Fig. 5.

50 Fig. 8 is a detail vertical sectional view taken through the valve on the plane indicated by the line VIII—VIII of Fig. 6.

Referring more particularly to the drawings, numeral 20 designates generally a press to which the attachment 21 may be applied. This attachment may be used with presses of varying char-

acteristics, but, for purposes of convenience, it is illustrated as applied to a hydraulic press of the type shown diagrammatically in my copending application Serial No. 669,657 filed May 14, 1948, now Patent No. 2,488,109. The press 20 is supported on a base 22 which may be suitably formed. The press includes a frame 23 of generally C-shape having a bolster section 24, a column section 25 and a head section 26, these sections being integrally joined. The frame contains a reservoir 27, a motor-driven pump 28, and a power cylinder 29, the latter being located in the head section and having a ram 30 projecting downwardly therefrom through a packing gland 31 fixed to the under side of the head section 26. 15 The ram 30 is provided with a rearwardly projecting arm 32, the outer end of which surrounds a shipper rod 33 utilized to govern the operation of a control valve 34, this valve being shown diagrammatically in Fig. 1. Such valve may be of many different types, the one illustrated conforming to that disclosed in the above-mentioned copending application.

Valve 34 is disposed in the outlet line of the pump 28 and functions to control the flow of fluid from the pump through lines 35 and 36 extending to the upper and lower ends, respectively, of the power cylinder 29. As in the copending application the valve 34 may be manually operated to effect the reciprocation of the piston 37 in the power cylinder. While the valve 34 has been shown and described in detail in the copending application mentioned, a brief description will be given here to facilitate an understanding of the press attachment forming the subject matter of this invention. Valve 34 includes a body 38 having a bore 40 formed therein together with a plurality of annular grooves spaced longitudinally of the bore 40, these grooves being designated by numerals 41 to 47, inclusive. Groove 45 is connected by a line 48 with the outlet of the pump 28 while grooves 43 and 46 are connected with lines 36 and 35, respectively, which lead to the lower and upper ends of the power cylinder 29. Groove 41 is connected by line 50 with reservoir 27, this line serving as the exhaust passage from the valve to the reservoir.

To control the flow of fluid to and from the power cylinder, bore 40 is provided with a spool 51 which is directly connected at its lower end 52 to the shipper rod 33 so that movement may be transmitted from the latter to the former in the operation of the press. Spool 51 is formed with an internal chamber 52 and a plurality of lateral ports 53 to 59, inclusive, certain ports registering with certain grooves in the body in various longitudinal positions of the spool. Chamber 52 is formed for the reception of a shuttle valve 61 which serves to connect various ports in the spool 51. Shuttle valve 61 includes a pair of longitudinally spaced lands 62 and 63 between which an annular groove 64 is formed, this groove providing a passage to connect certain lateral ports in the spool 51. The shuttle valve is also provided with a central socket 65 to receive the lower end of a coil spring 66, the opposite end of which is disposed in a socket 67 formed in a cap 68 applied to the open upper end of the spool 51. Spring 66 normally tends to urge the shuttle valve 61 downwardly to the lowermost position, illustrated in Fig. 1, and when the shuttle valve occupies this position the groove 64 connects grooves 45 and 43 so that fluid from the pump 28 may then flow from line 48 to line 36 which leads to the lower end of the power cylinder 29. When the shuttle

valve is so positioned, line 36 will be connected with reservoir 27 by groove 46, ports 58, chamber 52, ports 59, and line 58. The fluid under pressure supplied to the lower end of the power cylinder through line 36 will act upon piston 37 to move the same in an upward direction, the fluid above this piston being discharged through line 35 to tank 27. When the piston 37 approaches the limit of its upward movement, the arm 32 will engage a collar on shipper rod 33 and move the shipper rod, together with spool 51, upwardly until ports 58 are moved out of registration with groove 43. Fluid flow to the lower end of power cylinder 29 will then be discontinued and piston movement will stop.

Movement of the piston in the opposite direction, or downwardly, is initiated by raising the shipper rod 33 and spool 51 until ports 53 register with groove 42. At this time fluid may flow from line 48 upwardly in a bore 69 to a chamber 70 which is connected by a passage 71, with groove 42. Fluid admitted to this groove will flow through ports 53 into the lower end of chamber 52 beneath shuttle valve 61. This fluid under pressure will force the shuttle valve upwardly in opposition to spring 66 until the upper end thereof engages the bottom of the cap 67 at which time groove 64 will establish communication between ports 58 which are then in registration with groove 45, and ports 57 registering with groove 46. Fluid from the pump 28 may then flow from line 48 through line 35 to the upper end of power cylinder 29. The force of this fluid will move piston 37 downwardly forcing fluid from the lower end of the power cylinder through line 36 to groove 43 through ports 54 into transverse ports 71-A formed in the shuttle valve 61 at the land 62. Some of this fluid will flow downwardly through a reduced port 72 in the lower portion of the shuttle valve to the lower end of the chamber 52. This fluid will serve to maintain a pressure beneath the shuttle valve, which pressure will hold the shuttle valve in its elevated position in opposition to the force of the spring 66. The balance of the fluid flowing into passages 71-A will escape through passage 73 and sockets 65 and 67 to bore 74 which leads from chamber 52 to groove 47, this fluid then escaping through line 50 to reservoir 27.

While piston 37 is moving downwardly and fluid is being exhausted through line 36 and the path mentioned above, the shuttle valve will be held in an elevated position to continue to direct fluid flow from pump 28 to the upper end of the power cylinder. When this flow is initiated, some of the fluid supplied to groove 46 will flow through an angular passage 75 to a chamber 76 at the upper end of bore 69. This fluid may flow through ports 71 formed in a valve housing 78 and around a needle valve 80 adjustably positioned in this housing, to the space above a spring-elevated plunger 81. Fluid applied to the upper end of this plunger will force the same downwardly to discontinue the flow of fluid from line 48 to chamber 76 and the under side of the shuttle valve. Since, however, fluid being exhausted from the lower end of the power cylinder serves to hold the shuttle valve in its position, downward movement of piston 37 will not be interrupted.

When the piston reaches the lower limit of its travel in a downward direction, either through engagement with the lower end of the cylinder or the engagement of the ram 30 with an obstruction offering sufficient resistance to cause the re-

lief valve 79 to bypass fluid from line 48 to reservoir 27, fluid flow from the lower end of power cylinder 29 will be interrupted and spring 65 may then move shuttle valve 61 to its lowermost position, fluid pressure beneath the shuttle valve being dissipated through passages 72 and 73. When the shuttle valve drops in this manner, fluid under pressure will be directed to the lower end of the power cylinder to cause the piston to move in an upward direction. If the needle valve 80 is properly adjusted, plunger 81 will be moved upwardly by its spring forcing the fluid from the space above the plunger through the valve housing 78 and passage 75 to groove 46 from which it will flow to reservoir 27. When plunger 81 moves upwardly a sufficient distance, communication will again be established between line 48 and chamber 70 so that fluid under pressure may be again introduced to groove 42 to actuate the shuttle in opposition to the spring 65 causing the piston 37 to resume movement in a downward direction. The distance traveled in the reverse or upward direction by piston 37 will be determined by the setting of needle valve 80. The mechanism thus far described is identical with that set forth in the above-mentioned copending application, the operation thereof also being identical.

From the foregoing description it will be apparent that the ram 30 may be caused to reciprocate either throughout the full stroke by completely closing needle valve 80 or through shorter strokes the lengths of which are determined by the adjustment of the needle valve. As usual in hydraulic presses, the force exerted by the ram 30 will be determined by the area of piston 37 and the pressure on the fluid applied thereto. As pointed out in the objects, the attachment 21 has been provided to effect a multiplication or intensification of the force exerted by the ram 30. To secure this effect, the transmitter 82 of a hydraulic motion-transmitting mechanism is applied to the bolster 24 of the press 20. This transmitter includes a casting 83 having a chamber 84 formed therein. This chamber receives a piston 85 having a piston rod 86 projecting from the upper end, this piston rod is connected with the lower end of the ram 30 so that movement of the piston 37 in the power cylinder will be directly transmitted to the piston 85.

Chamber 84 is connected by a passage 87 with the upper end of a chamber 88 formed in the head 90 of the attachment frame 91, the head 90 being supported by corner posts 92 extending upwardly from a bolster 93. This bolster is held in horizontal registration with the bolster 24 of the press frame by a stand 94 formed of tubing or other suitable material, leveling means 95 being provided to secure the proper position of the bolster. The bolsters 24 and 93 are connected by side plates 96 which are bolted or otherwise secured to the sides of the press frame and the attachment frame. When the piston 37 in the power cylinder 29 moves downwardly, similar motion will be transmitted to the piston 85. This motion of piston 85 will discharge fluid from cylinder 84 through line 87 into the upper end of chamber 88. The force of this fluid will cause ram 97, which is slidably positioned in chamber 88, to move downwardly and impart similar movement to platen 98 which is guided for sliding movement on the corner posts 92. Downward movement of the platen is resisted by coil springs 100 which surround rods 101 projecting upwardly from the platen through openings in head 90,

the upper ends of these rods being threaded to receive nuts 102, which serve as abutments for washers 103 engaging the upper ends of springs 100. During the downward movement of the ram 97 and platen 98, springs 100 will be compressed so that when fluid pressure is relieved above the piston 97, the springs will return the piston 97 and the platen 98 to their elevated positions.

Casting 83 is provided with a horizontally extending bore 104 in which a ported sleeve 105 is disposed, this sleeve having longitudinally spaced sets of ports 106 to 109, inclusive, and slidably receiving a spool 111. This spool has a pair of annular grooves 112 and 113 formed therein for the purpose of connecting certain sets of ports in various positions of longitudinal movement of the spool. Normally, the spool is urged toward one end of the bore by a coil spring 114 having one end disposed in a socket formed in the spool and the other end positioned in a socket formed in a cap 115 employed to close one end of bore 104. A second cap 116 closes the opposite end of the bore, these caps also serving to maintain the longitudinal position of the sleeve 105. The left end of the spool 111, as viewed in Fig. 5, is also provided with a socket for the reception of a piston 117, the spool having ports 118 formed therein to establish communication between groove 113 and the socket at the inner end of the piston 117. Ports 109 in the sleeve 105 are in open communication with the lower end of chamber 84 through a passage 120 formed in the casting 83 while ports 108 are connected with the upper end of the chamber by a second passage 121, also formed in casting 83. When the spool 111 is normally positioned as shown in Fig. 5 communication between ports 108 and 109 is obstructed. Groove 112 in the piston, however, establishes communication between ports 107 and 108, at this time, the former ports being connected as shown in Fig. 1 by conduit 122 with reservoir 27.

It will thus be seen that, as piston 85 moves in a downward direction, fluid from reservoir 27 may flow through conduit 122, ports 107, groove 112, ports 108, and passage 121 to the upper end of chamber 84 to fill the portion of chamber 84 above the piston 85. If, in its downward movement, platen 98 engages an obstruction, fluid pressure in the upper end of chamber 88, in passage 87 and in the lower end of chamber 84 will increase. This pressure will be introduced through passage 120, ports 109 and 118 to the socket at the inner end of piston 117. This fluid pressure will react to urge spool 111 toward the right end of bore 104 in opposition to the spring 114. If the pressure is sufficiently high, spool 111 will be moved until groove 113 establishes communication between ports 108 and 109 and interrupts communication between ports 107 and 108. When ports 108 and 109 are connected, communication will be established between the opposite ends of chamber 84 and fluid may then flow from the lower end of chamber 84 to the upper end thereof above piston 85. It will be obvious that only the fluid displaced by the difference in area between the piston and the piston rod 86 will flow to the upper end of the chamber 84, the remaining fluid displaced continuing to flow into the upper end of chamber 88. It will thus be seen that the effective area of piston 85 will have been reduced to the area of the piston rod 86. The relation between piston 85 and ram 97 will therefore be changed causing the latter member to exert an increased force. The force exerted by ram 30 will thus be multiplied or intensified.

When ram 97 ceases to move, ram 38 will be stopped and shuttle valve 61 will be shifted to reverse the direction of ram 38. Piston 85 will then also be reversed and caused to move in an upward direction. As soon as pressure is relieved in the connected ends of chambers 84 and 88, spring 114 will shift spool 111 back to the position shown in Fig. 5 in which position communication between the ends of chamber 84 is obstructed. At this time the upper end of the chamber 84 will be connected directly with the reservoir 27, in the manner described above, and fluid displaced from the upper end of chamber 84 will flow to the reservoir. In the event there has been any fluid displaced or otherwise lost from the connected ends of chambers 84 and 88 it will be replaced through a check-valve controlled passage 123 formed in piston 85. This passage receives check valve 124 which is of the poppet type, being held in a normally closed position by a coil spring 125. From the foregoing it will be seen that reciprocatory movement of piston 37 will be transmitted to the ram 97 and platen 98. If the valve 34 is set to cause the piston 37 to execute short strokes the ram 97 and platen 98 will be caused to execute similar strokes at higher tonnage.

One of the features of the invention resides in providing a second relief valve 126, the inlet of which is connected with the upper end of the power cylinder 29. The control chamber of this relief valve is connected by line 127 with ports 106 in sleeve 105. Normally ports 106 are blocked by spool 111 but when this spool moves under the influence of pressure in the connected ends of chambers 84 and 88, groove 112 will establish communication between ports 106 and 107, thus connecting the control chamber of relief valve 126 with reservoir 27. Relief valve 126 may then respond to the pressure in the upper end of cylinder 29 to vent fluid from the same to the reservoir 27. It will be seen that relief valve 126 may therefore be set at a lower pressure than relief valve 79 so that the pressure developed by the attachment may be readily controlled. When the spool 111 returns to its normal position, the control chamber of the second relief valve 126 will again be blocked from the reservoir permitting the first relief valve to control the pressure existing in the system.

While the form of embodiment of the present invention as herein disclosed constitutes a preferred form, it is to be understood that other forms might be adopted, all coming within the scope of the claims which follow.

I claim:

1. In a hydraulic system, a source of fluid pressure; a power cylinder; a piston disposed for movement in said power cylinder; control means between said pressure source and said cylinder to cause reciprocatory movement of said piston; a second cylinder; a second piston disposed for movement in said second cylinder, said pistons being connected for movement in unison; a third cylinder; a third piston mounted for movement in said third cylinder; a fluid conductor connecting one end of said second and third cylinders; fluid conducting means connecting the opposite ends of said second cylinder; valve means in said last-mentioned fluid conducting means for normally preventing communication between the ends of said second cylinder; means responsive to fluid pressure in the connected ends of said second and third cylinder for actuating said valve means; and relief valve means for

controlling the effective pressure in the first cylinder when communication between the ends of the second cylinder is established.

2. In a hydraulic system, a source of fluid pressure; a power cylinder; a piston disposed for movement in said power cylinder; control means between said pressure source and said cylinder to cause reciprocatory movement of said piston; a second cylinder; a second piston disposed for movement in said second cylinder, said pistons being connected for movement in unison; a third cylinder; a third piston mounted for movement in said third cylinder; a fluid conductor connecting one end of said second and third cylinders; fluid conducting means connecting the opposite ends of said second cylinder; valve means in said last-mentioned fluid conducting means for normally preventing communication between the ends of said second cylinder; means responsive to fluid pressure in the connected ends of said second and third cylinder for actuating said valve means; and relief valve means for controlling the effective pressure in the first cylinder when communication between the ends of the second cylinder is established; said relief valve being normally inoperative and rendered operative by said fluid pressure responsive means simultaneously with the establishment of communication between the ends of said second cylinder.

3. Hydraulic apparatus comprising a source of fluid pressure; a double-acting power cylinder having a piston; control valve means between said pressure source and power cylinder, said valve means being operative to cause the repeated reciprocation of the piston in said power cylinder over a fraction of the normal stroke thereof; a second piston connected for movement with the first-mentioned piston; a second cylinder receiving the second piston; a third cylinder; means establishing communication between one end of said second and third cylinders; and means responsive to fluid pressures in the connected ends of said second and third cylinders for establishing communication between the ends of said second cylinder.

4. Hydraulic apparatus comprising a source of fluid pressure; a double-acting power cylinder having a piston reciprocable through a normal stroke; control valve means between said pressure source and power cylinder, said valve means being operative to cause repeated reciprocations of said piston through a fraction only of the normal stroke; a second cylinder; a second piston disposed for reciprocation in said second cylinder, said second piston being connected for movement in unison with said first piston; means for establishing communication between the ends of said second cylinder when said second piston is moving in one direction only; a single-acting power cylinder communicating with one end of said second cylinder; and means responsive to the pressure in the communicating ends of said second and third cylinders to establish communication between opposite ends of said second cylinder when said second piston is moving in the opposite direction.

5. Hydraulic apparatus comprising a source of fluid pressure; a double-acting power cylinder having a piston; means for controlling the operation of said piston including a fluid pressure reversing valve; means operative upon initial return movement of said piston for applying fluid pressure to said reversing valve to cause forward movement of said piston; a second piston con-

nected with said first piston for movement in unison therewith; a second cylinder receiving said second piston; a third cylinder in communication with one end of said second cylinder; a third piston disposed for reciprocation in said third cylinder; resilient means yieldably resisting movement of said third piston in one direction in said third cylinder; and valve means responsive to predetermined fluid pressure in said third cylinder to establish communication between opposite ends of said second cylinder.

6. Hydraulic apparatus comprising a source of fluid pressure having a reservoir; a relief valve communicating with said pressure source; a power cylinder having a piston and ram; control mechanism between said pressure source and said power cylinder, said mechanism being operative to cause the reciprocation of said piston; a second power cylinder having a second ram; a third cylinder having a third piston and a ram aligned with and engaged by the ram of said first-mentioned power cylinder; fluid conducting means connecting the ends of the second and third cylinders opposite the ram ends; a valve mechanism having a casing with a plurality of ports; fluid lines leading from ports in said valve casing to opposite ends of said third cylinder and from other ports to said reservoir and to the end of said first cylinder opposite the first ram; a second relief valve in the line leading to said first cylinder; and a valve member in said casing, said valve normally establishing communication between the ram end of said third cylinder and said reservoir and preventing operation of said second relief valve, said valve being responsive to fluid pressure in the end of said third cylinder opposite its ram to simultaneously interrupt such communication, establish communication between opposite ends of said third cylinder and render said second relief valve effective to control the pressure in the end of said first cylinder opposite the ram thereof.

7. Hydraulic apparatus comprising a source of fluid pressure including a reservoir; a relief valve communicating with said pressure source; a pair of aligned power cylinders having pistons and

10

rams, the latter being connected to cause said pistons to move in unison; means for controlling fluid flow from said source to opposite ends of the first of said pair of cylinders to effect reciprocation of both pistons; a third power cylinder having a ram; a conductor connecting an end of the second of said pair of cylinders with one end of the third cylinder; a second relief valve connected with the end of the first of said pair of cylinders opposite the ram thereof; means responsive to fluid pressure in said third cylinder for establishing communication between the ends of the second cylinder of said pair and rendering said second relief valve operative, said means having a casing with a plurality of ports two of which are connected with the ends of said second cylinder, another being connected with said reservoir and another being connected with the outlet of said second relief valve; and a spool disposed for movement in said casing, said spool normally preventing communication between the ports connected with the ends of said second cylinder and between the outlet of said second relief valve and said reservoir and establishing communication between the ram end of said second cylinder and said reservoir, a predetermined increase in pressure in the third cylinder serving to move said spool to simultaneously interrupt the communication between said second cylinder and said reservoir, establish communication between the ends of said second cylinder and connect the outlet of said second relief valve with said reservoir.
